UNITED STATES PATENT OFFICE.

FREDERIC S. JULIUS, OF EVANSTON, ILLINOIS.

DEVICE FOR TIGHTENING WIRES AND TWISTING THEIR ENDS TOGETHER.

Application filed August 17, 1925. Serial No. 50,559.

This invention relates to a tightening and twisting device, and particularly one which is adapted for use with wires or rods customarily employed in connection with concrete forms for foundations, walls, and similar structures, as well as in connection with structural members of buildings.

It is an object of the invention to provide a convenient and highly efficient device for tightening and twisting together the ends of wires or rods generally, and one in which both the tightening and the twisting may be simultaneously effected.

Further objects of the invention are to provide a device of the character referred to which is sturdy in construction, easy to manipulate, which will not readily get out of order, and which can be easily engaged and disengaged from the wires or rods being operated upon.

It is a special object to provide a device which will enable a workman to effectively tighten the wires or rods to any extent desired through the pressure of one hand upon the main body or handle of the device while leaving the other hand entirely free for bringing about the twisting of their ends.

It is also a special object to provide a device for the purpose noted, having an elongated body serving as a lever for tightening the wires or rods equipped with an especially shaped fulcrum foot intermediate its ends tending to steady the device during use, and also equipped at its extremity with a pair of rocking gripping jaws so mounted as to assure their proper relative disposition regardless of the variations in the position of the device, whereby to accommodate it to different characters of work.

These and other objects of the invention will more fully appear when taken in conjunction with the following description and the appended claims.

In the accompanying drawings, Fig. 1 is a side elevation showing the method of supporting the improved tightening and twisting device and the manner in which the ends of the wires or rods are gripped between the gripping jaws; Fig. 2 an end elevation of the parts shown in Fig. 1; Fig. 3 an enlarged fragmentary detailed view showing the structure of the supporting frame carried by the rotatable shaft, together with the manner of rockably supporting the gripping jaws therein; Fig. 4 a side elevation of the parts shown in Fig. 3; and Fig. 5 an

elevational view of the same parts looking towards the ends of the gripping jaws, and illustrating the method by which the jaws are normally positioned within the supporting frame.

Referring to the drawings, the body of the device is designated at 1, the said body being elongated, and one end of which is fashioned in the shape of a handle which is adapted to be gripped in the hand of the operator. Depending from a point intermediate the ends of the body, and preferably formed integral therewith, is a depending fulcrum foot 2, the base 3 of which is of considerable width and is provided with a flat bottom face as clearly indicated at 4, in Fig. 2 of the drawings.

Journalled for rotative movement in the body, and located adjacent the end thereof at one side of the fulcrum foot is a shaft 5 having fixed to its upper end a pinion 6, and at its lower extremity a supporting frame designated generally in the drawings by the numeral 7. This frame comprises a ring or annulus 8 which is adapted to embrace the lower end of the shaft 6, and is locked thereto by the transversely extending pin 9 which extends through both the annulus 8 and the shaft 5. Preferably formed integrally therewith and depending from the annulus 8 are two pairs of curved fingers 10, 10', and 11, 11'. Mounted for rocking movement on the pair of fingers 10, 10' is a gripping jaw 12 having its inner face slightly curved and serrated as clearly shown in Figs. 1 and 5 of the drawings, and provided at the lower portion of its outer face with two pairs of spaced-apart lugs indicated at 13, 13', respectively, these lugs are perforated as well as the lower extremities of the fingers 10, 10', and serve as a means for rockably supporting the jaw within the frame 7. Cooperating with the jaw 12 and positioned opposite thereto is a similar gripping jaw 14 rockably supported within the frame in a similar manner, being pivoted to the lower extremities of the fingers 11, 11'. For the purpose of resiliently urging the upper portions of the jaws toward each other, the opposite ends of a coiled spring 15 are attached to projections 16 and 17 extending upwardly from the respective jaws.

A spindle 18 is anchored in the body 1 at one side of the shaft 5, and has journaled thereon the gear 19 which meshes with the pinion 6. Attached in any suitable manner

to the gear 19 is an actuating handle 20 which may be locked in position by the locking nut 21.

In Figs. 1 and 2 there is illustrated a beam 5 or joist on the upper face of which the fulcrum foot is adapted to rest, with a wire or bent rod 23 encircling the beam and having its upper free ends 23' and 23" projecting between the serrated faces of the 10 gripping jaws 12 and 14, and in position to be gripped thereby. This illustration has been made merely for the purpose of more clearly depicting the manner in which the invention is used.

15 In use, the ends of the wires or rods to be operated upon, are projected between the serrated faces of the gripping jaws in the manner clearly shown in Figs. 1 and 2, an effective gripping action being maintained 20 upon the wires during an upward pull upon the jaws, as will be obvious from an inspection of the drawings.

In order to tighten the rods or wires, it is merely necessary for the operator, who 25 grips the handle portion of the body in one hand, to press downwardly thereupon with sufficient force to tighten or stretch the wires to any desired extent. This is brought about due to the fulcrum provided by the depending fulcrum foot 2-3, downward pressure 30 upon the handle portion shown at the left hand side of Fig. 1 causing the gripping jaws to be lifted upwardly or away from the beam 22. After the wires or rods have 35 been tightened to the extent desired, the crank handle 20 is turned by the operator who grips it with his other hand so as to rotate the shaft 5. Rotation of shaft 5, in turn, causes a bodily rotation of the pair 40 of gripping jaws 12 and 14 which results in twisting the free ends of the wires together in an obvious fashion.

After the twisting of the ends has been 45 accomplished, the wires may be readily released from the jaws by lifting slightly upwardly upon the handle of the device, supplemented by a slight pressure upwardly upon the bottom faces of the gripping jaws.

It is noted that the bottom face 4 of 50 the base 3 of the fulcrum foot is of considerable width, as viewed in Fig. 2, and contacts the beam 22 throughout a substantial extent. This produces a steady action preventing the device from tilting sidewise 55 during its use, and enabling the operator

to easily balance the device under varying conditions found in actual practice. Attention is also directed to the presence of the spring 15 for urging the upper portions of the gripping jaws toward each other, not only assisting in assuring a more satisfactory gripping action upon the wires or rods, but also serving to positively maintain the desired disposition of the jaws within the supporting frame regardless of the position of the device during use.

It is thus seen that the invention provides a very sturdy, efficient, and convenient tool for simultaneously tightening and twisting wires or rods, both the tightening and twisting action being constantly under the control of the operator. Although the invention has been illustrated in connection with but a single form of beam or building element, it is contemplated using the invention generally for the tightening and twisting of rods or wires in any analogous situation.

As required by the patent statutes, the preferred embodiment of the invention has been illustrated and described in detail. It is obvious, however, that many changes may be made both in structural details and in the arrangement of the several parts without departing from the spirit of the invention. It is therefore not intended to limit the invention beyond that particularly defined by the appended claims.

I claim:

1. A tension and twisting device comprising a fulcrum lever one end of which 80 constitutes a handle, a work spindle journaled for rotation in the other end of said lever, a manually operated gear drive for actuating said spindle, a forked bracket secured to said spindle and adapted to rotate 85 therewith, and a pair of gripping members pivotally mounted on said bracket.

2. A tension and twisting device comprising a fulcrum lever one end of which constitutes a handle, a work spindle journaled 100 for rotation in the other end of said lever, a manually operated gear drive for actuating said spindle, a forked bracket secured to said spindle and adapted to rotate therewith, and a pair of serrated gripping members 105 pivotally mounted on said bracket in such manner that their cooperating gripping faces are normally engaged.

In testimony whereof I sign my name.

FREDERIC S. JULIUS.
